UNITED STATES PATENT OFFICE

DOUGLAS E. STEVENS, OF DENVER, COLORADO

FLANGING MACHINE

Application filed July 30, 1929. Serial No. 382,159.

This invention relates to improvements in flanging machines.

In places where sheet metal is worked into different articles, as for example in boiler works or other places where sheets of steel are cut and bent into shape to incorporate them into different articles of commerce, it often becomes necessary to flange the edges of the plates. The flanges are sometimes 10 straight and at other times concave or convex.

It is the object of this invention to produce a simple and substantial machine that shall be especially well adapted for flanging plates 15 of any thickness and by means of which flanges of different curvatures and of different angles can readily be produced.

It is a further object of this invention to produce a flanging device of such construction 20 that it can be attached to an ordinary punch press and operated by means of this press, and which is, therefore, especially well adapted for use in shops that are provided with such punch presses.

25 This invention briefly described consists of a flanging block which is adapted to rest upon the upper surface of the supporting table of a punch press. This block is provided with a transverse recess, one side of 30 which has a perpendicular wall and the other side of which is formed by a cylindrical surface. On one side of the recess the block is provided with an upwardly extending lug, to which a plate clamp has one end pivotally attached.

35 The plate clamp carries a flanging arm which is pivoted thereto, and which is rotatable, about an axis that is parallel with the plane of the vertical wall of the recess. A main bearing block is secured to the plunger 40 of the punch press, and this block is provided with downwardly projecting lugs, between which a lever is pivoted. The main bearing is provided at one end with a lug that is adapted to be engaged by the corresponding ends of the lever. A spring is interposed 45 between the other end of the lever and the bearing block and tensioned so as to normally hold the lever with one end against the under-surface of the stop. One end of the lever 50 is connected with the free end of the plate

clamp by means of two links, and the other end of the lever is connected with the flanging arm by means of other links. When the plunger of the punch press moves upwardly and downwardly in the usual operation of the 55 press, the clamp plate and the flanging arm move as a unit as long as the plate clamp is free to move and when the latter stops, due to its engagement with the upper surface of the plate to be flanged, the flanging arm is 60 rotated about its pivot and bends the edge of the plate, all in a manner which will hereinafter be more fully described.

Having thus briefly described the invention, the same will now be described in detail, 65 and for this purpose reference will be had to the accompanying drawings, in which the preferred embodiment of the invention has been illustrated, and in which;

Fig. 1 is a side elevation of my improved 70 flanging machine.

Fig. 2 is a section taken on line 2—2 Fig. 1.

Fig. 3 is a section taken on line 3—3 Fig. 1, and shows the shape of the die plates employed when a straight flange is to be bent.

Fig. 4 is a section similar to that shown in Fig. 3, but showing the shape of the die plates when a convex flange is to be bent.

Fig. 5 is a view similar to those shown in 80 Figs. 3 and 4, and shows the shape of the dies employed when a concave flange is to be bent.

Fig. 6 is a section taken on line 6—6 Fig. 2.

Fig. 7 is a section taken on line 7—7 Fig. 6. 85

Fig. 8 is a fragmentary section through one side of the plate clamp, taken on line 8—8 Fig. 7, and

Fig. 9 is an end view of the flanging arm.

In the drawing numeral 1 indicates the supporting table of a punch press or of a similar machine, and numeral 2 indicates by means of dotted lines the lower end of the plunger which forms part of the punch press. Secured to the lower end of the plunger is a 95 main bearing which has been designated by numeral 3, and which is provided on its under side with two spaced downwardly extending lugs or ears 4, between which the lever 5 is mounted, and to which it is pivotally attached 100

by means of a steel pin 6. The lower surface of the main bearing blocks is also provided with a downwardly projecting stop 7, against which the corresponding end of the lever is 5 adapted to rest when the parts are in normal or inoperative position. Extending forwardly from the lugs 4 is a projection 8 that forms an abutment for the upper end of a helical compression spring 9, whose lower end 10 rests on the upper surface of the corresponding end of lever 5. Resting upon the surface of table 1 is an adjustable support consisting of a base member 10, one end of which has an upwardly extending wall 11. The upper surface 15 of member 10 is inclined with respect to the under surface thereof, and this inclined surface has been designated by reference numeral 12. Supported on the inclined surface 12 is another wedge shaped member 13, the angle between whose opposite sides is the same as the angle between the inclined surface 12 and the base of supporting member 10. These two members are assembled in the manner shown in Fig. 1, and form a support 20 for the flanging block which will presently be described. A screw 14 has a threaded connection with one end of the wedge shaped block 13, and is rotatably mounted in the vertical wall 11. This screw is held against 25 longitudinal movement with respect to wall 11, and therefore when it is rotated it will move member 13 relative to member 10, and in this manner will alter the distance between the upper surface of member 13 and the lower 30 surface of member 10. This adjustment will be hereinafter referred to.

Resting on the adjustable support, which has just been described, is a flanging block which consists of a block 15 whose bottom surface 16 lies in a single plane. The rear vertical side of this block is bounded by a plane 17 that makes an angle of 90 degrees with plane 16, and this vertical surface terminates in an incline surface 18 that extends between the vertical surface 17 and the vertical 40 surface 19. From the upper edge of surface 19 the block is provided with a forwardly extending surface 20 that is parallel with the bottom 16, and this terminates in a vertical surface 21, from the upper edge of which a plane surface 22 extends forwardly parallel with the base and terminates in an incline surface 23, which is connected with the base by means of the vertical surface 24 and the 45 vertical surface 25. Each end of this block is provided with a recess 26 to which attention will hereinafter be directed. A flanging die which in the embodiment shown in Figs. 1 and 6 is formed from tool steel made in the shape 50 of an angle iron having flanges 27 and 28 which are located at right angles to each other. This die is held in place by means of screws 29. The other part of the flanging block has been designated by reference 55 numeral 30 and is of substantially rectangular

shape, but is provided on its front upper corner with a cylindrical surface 31, and has extending upwardly from its upper surface a lug 32. The front end of block 30 fits against the vertical surface 17 and is held in proper alignment with respect to block 15 by means of a key. The rear corners of block 30 are provided with rectangular notches 33, corresponding to notches 26 in the corners of block 15. Blocks 15 and 30 are held in assembled 70 relation by end plates 34. These end plates are of the shape shown in Fig. 1, and are provided at opposite ends with inwardly extending lugs 35 that are adapted to engage in the notches 26 and 33 in the manner shown in 75 Fig. 2. These end plates are held in position by means of bolts 36, and in order to assure perfect alignment between the parts, keys 37 are located between the end plates and the two parts of the flanging block in the manner 80 shown in Fig. 2. The flanging block which has just been described is supported on the adjustable support as shown in Fig. 1.

Pivots attached to lug 32 and rotatable about the axis of the steel pin 38 is a plate 90 clamp which has been designated as a whole by reference numeral 39. This clamp has two rearwardly extending spaced parallel arms 40, between which the lug 32 is located and which are provided with openings for the reception of the pivot pin 38. The front end of the plate clamp is provided with two spaced recesses 41, in which are located the lower end of links 42. These links are provided with openings for the reception of the 95 steel pivot pin 43. The upper ends of links 42 are pivotally connected with the front end of lever 5 by means of the steel pivot pin 44. The plate clamp is provided with two semi-circular bearings 45, one of which is shown 100 quite clearly in Fig. 8, and both of which are shown in Fig. 7. Located between the arms 40 of the plate clamp is a flanging arm 46. This flanging arm is provided with two trunnions 47 that are adapted to rest in the bearings 105 45, in the manner shown in Fig. 7. The flanging arm has a cylindrical surface 48 that extends through an arc of slightly greater than 90 degrees and which terminates in an inclined end portion 49. Arm 46 is provided 110 with two recesses 50 which are adapted to receive the lower ends of the links 51 that are pivotally connected with the arm by means of a steel pin 52. The upper ends of links 51 are attached to the rear end of lever 5 by 115 means of a steel pin 53. When the parts are in the position shown in Fig. 6 and when the machine is in inoperative position, surface 54 of arm 46 is held in a position parallel with the vertical surface 55 of the plate clamp, 120 but when the main bearing block is moved downwardly from the position shown in Fig. 6, the lever 5 will be forced to rotate about pin 6 for the reason that when the plate clamp 125 comes in contact with the upper surface of 130

plate 56 it stops and the bearing block can therefore continue to move only by rotating the flanging arm about the axis of trunnions 47. The maximum extent of the rotation of the flanging arm is 90 degrees, which brings it into the position shown in Fig. 1.

The undersurface of the plate clamp is provided with a steel face plate 57 that is secured to it by means of screws. The surface 58 of the flanging arm is provided with a recess in which is located a removable steel plate 59 that is secured in place by means of screws 60. Plate 59 can be replaced by plate of different shapes in the manner shown in Figs. 3, 4, and 5, where plate 59a and 59b show respectively die plates having concave and convex surfaces, which cooperates with the convex and concave surfaces 28a and 28b of the die plate that is attached to the flanging block.

Having now described the construction of the machine, I will now describe the operation thereof. It is obvious that if the bearing block 3 is moved upwardly from the position shown in Fig. 6 there will be no appreciable change in the relationship of the several parts attached to it. Spring 9 will hold the rear end of lever 5 against the bottom of stop 7, and the only reason why an alteration in the respective position of the parts takes place is that the plate clamp moves about the center of the pivot 38, but as the angular movement is comparatively small, the changes effected thereby are not appreciable.

Let us now assume that the parts are in the positions shown in Fig. 6 and that a plate 56 is inserted between the adjacent surfaces of the die plates 57 and 27 until it is in the position shown. Let us now further assume that the machine is operated so as to move the plunger 2 downwardly. As soon as plate 57 strikes the upper surface of plate 56, further movement of plate clamp will cease and therefore as the plunger 2 continues to move in a downward direction, lever 5 will begin to rotate about its pivot 6 and the rear end thereof will begin to move away from stop 7, thereby rotating the flanging arm until the parts reach the position shown in Fig. 1, in which position the flanging arm has been rotated through an angle of 90 degrees. As 90 degrees is usually as large an angle as it is necessary to bend a flange this is as a rule the extreme limit, but by properly modifying the dies a flange can be bent through a greater angle than 90 degrees.

It will be seen from an inspection of the drawing that the angle through which the flanging arm is rotated can be varied by adjusting the position of the flanging block with respect to the movement of bearing 3. As the flanging block does not begin to move until the plate clamp has engaged the upper

surface of the plate, it is evident that by moving the flanging block downwardly the plate clamp will come into contact with the plate at a later period and therefore the flanging arm will rotate through a smaller angle. The adjustable support comprising members 10 and 13 therefore constitute means for controlling the angle through which the flange is bent. By this machine a comparatively short section of flange is bent at a time and the plate is therefore moved while the parts reciprocate and for each operation of the machine a certain length of flange is bent to the desired angle. If the flange is to be bent through an angle less than 90 degrees, the die plates 28 and 59 must be modified so as to conform to the angle of the finished flange.

From the above description it will be apparent that I have produced a simple mechanism that can be attached to an ordinary punch press and by means of which metal plates can readily be flanged either along perfectly straight edges or concave or convex edges as the case may be. Attention is called to the fact that this device is provided with means for first clamping the plate so as to hold it securely in position while the edge is being bent, and then after the plate has been clamped bending the edge to the angle desired. I also want to call attention to the fact that the pressure exerted by the clamping means is proportional to the force required to bend the plate, and, therefore the plate will always be securely held regardless of the amount of force required to turn the edge thereof.

Having described the invention what is claimed as new is:

1. A flanging machine comprising, in combination, a stationary flanging block, a clamping member, a main bearing block mounted for movement towards and away from the flanging block, a lever pivoted intermediate its ends to the main bearing, a plate clamp, links extending from the plate clamp to one end of the lever, a flanging arm pivotally connected with the plate clamp, links connecting the other end of the lever with the flanging arm, a stop for one end of the lever and resilient means for normally holding the lever against the stop.

2. In a flanging machine of the class described, in combination, a flanging block adapted to be supported on the upper surface of a table, an adjustable spacer between the block and the table, a plate clamp located above the clamping block, means for moving the plate clamp towards and away from the flanging block, a flanging arm pivotally connected with the plate clamp, and means for producing relative rotary movement between the flanging arm and flanging block where the latter remains stationary with respect to the flanging block.

3. In a flanging machine of the class described, in combination, a flanging block having a transversely extending recess in its upper surface, one side of said recess being formed by a vertical wall and the other side being formed by a cylindrical surface of substantially ninety degrees angular extent, a main bearing mounted for movement towards and away from the flanging block, a lever connected to the bearing block by a transverse pivot which extends through the lever between its ends, a plate clamp having one end pivotally connected with the flanging block on that side of the recess that is formed by the cylindrical surface, the other end of the plate clamp being connected with the corresponding end of the lever by means of a plurality of links, a flanging arm pivotally connected with the plate clamp and constrained to rotate about an axis parallel with the vertical side of the recess, links connecting the other end of the lever with the flanging arm and resilient means associated with the lever for normally holding it in a predetermined position.
4. A flanging machine comprising a flanging block adapted to rest upon a stationary table, said block having a recess that has a transverse vertical wall, the flanging block having an upwardly extending lug on the other side of the recess, a plate clamp having two arms that embrace the lug and are pivotally connected to it, a flanging arm pivoted to the plate clamp and rotatable about an axis that is parallel with the transverse vertical wall, a lever, links connecting one end of the lever with the free end of the plate clamp, links connecting the other end of the lever to the free end of the flanging arm, and a main bearing block pivoted to the lever between the pivot points of the links.
5. A flanging machine comprising a flanging block adapted to rest upon a stationary table, said block having a recess that has a transverse vertical wall, the flanging block having an upwardly extending lug on the other side of the recess, a plate clamp having two arms that embrace the lug and are pivotally connected to it, a flanging arm pivoted to the plate clamp and rotatable about an axis that is parallel with the transverse vertical wall, a lever, links connecting one end of the lever with the free end of the plate clamp, links connecting the other end of the lever to the free end of the flanging arm, a main bearing block pivoted to the lever between the pivot points of the links, a stop carried by the bearing block in position to be engaged by that end of the lever to which the links are connected that join the lever to the flanging block, and a spring interposed between the other end of the lever and the main bearing block.
6. A flanging device comprising, in combination, a flanging block having a recess ex-

tending transversely thereof, said block being formed of two parts, means for holding the parts in alignment, the block having an upwardly extending lug on one side of the recess, a plate clamp having one end pivoted to the lug, a flanging block pivotally attached to the plate clamp, means for moving the plate clamp and the flanging block simultaneously about the pivotal connection of the former with the lug and for moving the flanging block about its pivotal connection with the plate clamp when the latter is stationary.

In testimony whereof I affix my signature.
